HOLLOW BLOCK MASONRY CONSTRUCTION

Frederick Heath, Tacoma, Wash., assignor to
 The Heath Unit Tile Company, Tacoma,
 Wash., a corporation of Washington

Application October 31, 1935, Serial No. 47,648

6 Claims. (Cl. 72—41)

This invention relates to improvements in hollow block masonry construction, and more particularly to what is known as structural burned clay hollow tile, and is concerned with a new formation of the tile, new proportioning of dimensions thereof to increase the adaptability in use, and finally with wall constructions composed in part or in whole of these tile.

The general object of my invention is to provide hollow building blocks of a simple design which may be readily extruded in the forming machine and burned without cracking; which, while light in weight, will have load bearing and bracing webs positioned to resist all stresses encountered in structural walls; which will be so proportioned that all the parts of a wall may be built in systematic bonding relation whether the wall is made all of blocks or in conjunction with brick, and will have such form that the blocks may readily associate themselves with all the structural details, such as corners, jams, pilasters, chases, etc., resulting in strength and economy of construction.

In accomplishing the above object, I provide a primary block having a length equal to the length of a standard brick; a height equal to the combined thickness of three bricks and two intervening mortar joints, and a width which is an arbitrary amount independent of brick dimensions, but is preferably substantially six inches.

It results from the stated dimensioning that when my blocks are used with a facing course of one tier of brick lying flatwise one above the other, a wall is produced of substantially ten and one-quarter inches thickness, which is about midway between eight inch and twelve inch walls, produced by brick alone. I have found that for a great many uses an eight inch wall lacks the desired thickness to support the load and provide lateral stiffness, while the next standard dimension, namely, twelve inch, is greater than necessary. My ten and one-quarter inch wall meets the structural requirements of many buildings, such as residences and panel walls of skeleton frame construction, and thus not only saves material and expense but enlarges the rooms correspondingly.

Another characteristic of a wall with my tile and facing of brick is that there are no through mortar joints, with a result that the walls are kept dry. Furthermore, by the use of my tile I may build insulated walls in which there are substantially no continuous air passageways, the blocks being so laid in the wall that the cells

of each block are sealed at the ends by faces of the adjacent blocks crossing such ends.

Finally, my blocks are so made that if laid up in a single course to produce a substantially six inch partition wall, the formation of the block gives great strength to the wall while the mortar joints at the ends of the blocks are keyed to each block by reason of small cells in the blocks adjacent the opposite sides, as hereinafter explained.

My hollow block and walls made thereby or in conjunction with brick, are illustrated in the drawings, from which it will be seen that the system of construction employs blocks of two different characters each character of block having various fractional formations as illustrated on one hand by Figs. 1 to 4 inclusive and on the other by Figs. 5 and 6. Listing the different views of the drawings, Fig. 1 is a perspective of the primary block unit of my masonry construction, which has a length and height equal to the length of one standard brick (also equal to the thickness of three bricks plus two intervening mortar joints) and a width independent of brick dimensions, preferably six inches. Fig. 2 is a perspective of what I call a half-block, which has a width and length equal to the block of Fig. 1 and a height equal to half the height of the block of that figure less half the thickness of a mortar joint; Fig. 3 is a perspective of what I call a two-thirds block, which has a height and width equal to the block of Fig. 1, but a length equal to the thickness of two bricks plus a mortar joint. Fig. 4 is a perspective of a stepped block, which is of the same extreme dimensions as the block of Fig. 1, but with a cut-out portion, which, measured lengthwise of the voids, is equal to the thickness of one brick plus a mortar joint, and has a transverse extent equal to a brick width plus a mortar joint. Fig. 5 is a perspective of the primary unit of the second character of block, having the length and thickness of a standard brick and a width corresponding to the block of Figs. 1 to 4. Fig. 6 is a perspective of a block having a length and height of the block of Fig. 5, but a width of substantially one-third thereof. Fig. 7 is a vertical section through a wall made by a single tier of brick with headers and employing my blocks of Figs. 1 and 4 for back-up purposes. Fig. 8 is a perspective of the wall of Fig. 7. Fig. 9 is a vertical section of a wall employing the blocks of Figs. 1, 3 and 6 for back-up purposes. Fig. 10 is a perspective of the wall of Fig. 9. Fig. 11 is a perspective of a so-called six-inch wall made by the blocks of Fig. 1

with the blocks of Figs. 2 and 5 adjacent the corners. The upper course of brick in this view is supposed to rest directly in the mortar bed, surmounting the lower courses shown. Fig. 12 is a perspective of what I have called a quarter block, being a block having the width and height of Fig. 2, but a length equal to half that block less half a mortar joint. Figs. 13 and 14 are illustrations of patterns bonds which may be made by employing the blocks of Figs. 1, 2 and 12, and are intended to be illustrative of various arrangements which may be made by my blocks.

Referring to Fig. 1, the primary block, designated A, is shown as comprising an exterior shell 15 consisting of the vertical members 10 and 11, horizontal members 12 and 13. In the interior of the block are two vertical webs 14 and 15 extending the entire height of the block and joined at their tops and bottoms with the horizontal shell portions 12 and 13 and joined at their outer sides with the vertical shells 10 and 11 by means of cross portions 16 arranged to leave a series of voids between the web and shell. That block also has two intermediate horizontal centrally located webs 17 and 18 which are spaced apart a distance corresponding to the thickness of a mortar joint and at their ends join the vertical webs 14 and 15.

The formation thus described results in a block 30 with a series of voids running from end to end and open at the ends. There are two major voids 20 and 21 bounded by the internal vertical webs and the internal horizontal webs and the horizontal members of the shell. There is an intermediate 35 shallow void 22 between the internal horizontal webs 17 and 18 which void extends from the inner face of the vertical web 14 to the inner face of the web 15 and has a height equal to that of a mortar joint. The voids between the vertical web 40 14 or 15 and the adjacent vertical shell member 10 or 11 comprise a small tubular passageway 23 horizontally aligned with the intermediate void 22 and two voids 24 and 25, one above the other and elongated vertically in an oblong fashion 45 so that they extend directly opposite practically the entire major void 20 or 21.

The above defined construction of the interior of the block produces, when the block stands as shown in Fig. 1 or is laid vertical as in Fig. 11, 50 four load bearing members for each block, namely, the parts 10, 14, 15 and 11. The transverse shell members 12 and 13 which are preferably slightly thicker than any of the vertical members individually, provides an effective mortar bed with 55 ample strength to bridge the major void when the block is horizontal and with sufficient cross-section to form an effective column when the block is laid with the voids vertical. The two intermediate webs 17 and 18 very effectively brace 60 the side members. Finally, the small voids provide space into which the mortar will pass sufficiently to key the mortar effectively to the block.

By providing the two vertical webs 14 and 15 set in from the shell members 10 and 11 and 65 periodically connected therewith by the portions extending across the small voids, I accomplish several valuable results. First, I obtain the desired amount of material for load bearing purposes without making a wall so thick that it is 70 difficult to extrude or burn. By maintaining all of the thicknesses of nearly the same amount, I very materially reduce the unevenness of drying of different portions with its consequent liability to cracking the product. Second, by arranging 75 the intermediate webs 14 and 15 within the block

instead of providing simply a thicker wall, I reduce the span of the horizontal members 12 and 13 of the shell and thus form a more effective support for the same when the block is laid horizontally, and a more effective bracing when these members stand as columns with the block laid vertically. Finally, the end portions of the webs and shells provide ample mortar beds for the ends of the block while allowing such bed to be keyed to the block by reason of the minor voids shown. 10

The relative dimensioning of my blocks is also an important factor in the result accomplished. Modern brick have a length equal to the thickness of three bricks plus two mortar joints, and I use such dimension as the key dimension to 15 the length and height of my block; that is to say, the side face of my primary block is square, the height and length being equal to a length of brick, while the transverse dimension, as already stated, is preferably six inches. 20

I find that very convenient subdivisions of this block for building walls comprise the half block shown in Fig. 2, and designated B, which may be made by simply breaking the block of Fig. 1 through the line of middle voids 23—22 or may be extruded individually, while by cutting the block of Fig. 2 in half by a line of severance parallel with the end, I produce the so-called quarter block G, shown in Fig. 12, which standing on end is very suitable for a closure. The block C of Fig. 3 has the interior formation of the block of Fig. 1, but is substantially two-thirds the length thereof; and finally, the block D of Fig. 4 is the same as the block of Fig. 1 with the step cut out of it, which step is dimensioned to receive the 30 projecting portion of a header course with proper horizontal and vertical mortar joints. 35

The blocks of Figs. 5 and 6 are built on a different basis. The block E of Fig. 5 has the brick length and the substantially six-inch width of 40 Fig. 1, but has a height equal to that of one brick. This block is made in three connected units, that is to say, it has horizontal shells 30 and 31 extending from one side to the other and vertical shells 32 and 33, and four intermediate 45 vertical webs 34. This produces three units, each having a void 35, while there are two minor voids 36 between the intermediate unit and each of the extreme units, each minor void having its short dimension equal to the thickness of a mortar joint. When this block is severed through one of the minor voids, it produces the single unit block F shown in Fig. 6. 50

Now in building a ten and one-quarter inch wall with a course of facing brick and my blocks, 55 I may combine either the blocks of Figs. 1 and 4 or the blocks of Figs. 1, 3 and 6. Figs. 7 and 8 illustrate the first of these combinations wherein the blocks A and D are alternated one above the other and the facing of brick comprises running courses P and occasional header courses Q which extend into the space provided by the steps of the block D. In Figs. 9 and 10 the backing wall 60 comprises the blocks C, F and A repeating in that manner, thus leaving spaces between the block C and the block A for a header course. 65

In standard brick-laying it is customary to make every sixth course a header course, and my system of tile units is adapted for such laying, as illustrated in Fig. 9, where the two header courses appear at Q and the five intermediate running courses at P. It will be seen that the block C plus the block F takes the place of the stepping block D, so that the same system of brick 70 75

facing with header courses is adapted for either system of backing.

Fig. 11 illustrates two walls meeting at a corner composed of the blocks A, B and E. The lower course is shown as having a corner block B standing on end and then a block A standing sideways extending toward the right followed by a block A endwise, two blocks sidewise, one endwise, and so on. At the left of block B, that is, adjacent to its smaller side face, I place the block E standing on end, which overlaps and bonds with the block A at the right of block B, and then beyond the block E toward the left I indicate two blocks, a horizontal and one vertical, and so on. Now the surmounting course, which in the figure is shown raised for clearness of illustration, has at the corner the blocks B and E, but now with the wide dimension of block B extending in the other direction and with the block E at the right of B instead of at the left. Then toward the left I employ one block A flatwise and then a block A vertically, and to the right of block E I employ two flatwise blocks A instead of one flatwise block as in the lower course.

The illustrative arrangement just described causes the second course to bond very effectively with the first course. For instance, the mortar joint between the corner block B and the block E and the joint between the block E and the block A of the upper course, come on the flat face of a block A of the lower course; while the mortar joints between the blocks E, B and A of the lower course come against a flat face of this lower and upper course block A. The junction of the two adjacent horizontal blocks A of the upper course comes over the center of the vertical blocks A of the lower course, and the vertical blocks A of the upper course bridge the space between two horizontal blocks of the lower course, and so on.

In the described method of laying the wall, it will be seen that each course is effectively bonded with the adjacent course. Moreover, except as to the corner blocks B, the voids of each block are sealed at the end of the block by the flat face of adjacent blocks extending across them. Moreover, the small voids adjacent the shells of my blocks and the intermediate transverse void form spaces for keying the mortar bed across such end whether the blocks are end-set or laid flatwise.

Sometimes it is desirable to lay up all tile with the faces exposed in the form of an attractive pattern. My block units are admirably adapted for this purpose, as illustrated, for instance, in Figs. 13 and 14, composed of the blocks A, B and G, the blocks B having their voids extending horizontally and blocks A and G have them extending either horizontally or vertically as desired, the solid face of all of the blocks being aligned in the visible wall.

The pattern formation of Fig. 13 gives a mortar bed R over two blocks B and beneath one block A and two blocks G; a mortar bed S over one block A and two blocks G, and then one continuous horizontal mortar bed T over the blocks A and B, and various vertical mortar beds at the edges of each block. This wall unit, which one might call a block and a half high, is successively repeated, one course above the other, as the wall is laid out, producing the attractive pattern shown.

Fig. 14 illustrates another pattern arrangement of these blocks wherein the blocks A are laid up in step fashion one directly above the other and the space filled in at the top and bottom by blocks B and G and the small square spaces filled by the blocks G, as shown. This gives the pattern illus-

trated with comparatively short horizontal and vertical mortar beds. Various other attractive patterns may be made by suitably grouping the block units shown.

When the blocks are to be used to produce a pattern, they may be smooth or given such texture face as desired. For back-up purposes or plastered walls, the blocks are scored in the usual manner, as illustrated, for instance, in Fig. 1.

It will be apparent from the description given that I have produced a system of wall construction by the use of a comparatively few different units of hollow tile, which provides for laying up of the tile in various manners; enables the voids of each block to be sealed by reason of the flat faces of adjacent blocks, and enables the very ready production of a brick-faced wall of a very desirable thickness greater than that of two brick courses without resorting to the thickness of three brick courses.

When the blocks are used for back-up purposes in conjunction with brick the course of horizontal blocks associated with each course of end-set blocks, as illustrated in Figs. 7 and 9, prevents the accumulation of mortar in the bottom of the wall, which is a disadvantage resulting with the usual end-set tile construction. With my wall, the mortar droppings are arrested by each side-set tile course.

If it is desired to provide a twelve-inch wall, this may be very readily effected by using two tiers of my six-inch tile blocks suitably bonded at desired intervals. This bonding may, for instance, be effected by placing a course of the blocks E end-set across the mortar line between the two tiers and facing this intermediate course by end-set blocks E on each side.

As my building blocks have a width substantially midway between a single tier of bricks and two tiers it follows that by the conjoint use of brick and tile I may provide for walls of any desired thickness differing by a modulus of two inches instead of merely the present brick difference of four inches. To illustrate: a six-inch partition may be made by a single tier of my blocks; an eight-inch wall by two brick tiers; a substantially ten-inch wall by my blocks and one brick tier; a twelve-inch wall by two tiers of my block; a fourteen-inch wall by my blocks faced with brick on opposite sides, and so on. By thus cutting in half the unit of difference between successive widths of wall, walls can be built to fulfill more accurately the stress requirements at any particular location, with greater economy and an increase in the resulting space within the building.

I claim:

1. A masonry construction made of hollow building blocks and mortar, each block being of rectangular cross section and having two internal webs adjacent to and parallel with their longer faces and periodically connected therewith in a manner to form minor voids which are no wider than the webs, and having major voids extending from end to end, said construction comprising a course of blocks such as aforesaid some of the voids of which are horizontal and some of which are vertical, and a surmounting course such as aforesaid with the blocks having their voids vertical where they were horizontal in the lower course and horizontal where they were vertical, whereby four vertical load-supporting members are provided by each block and the voids of each block are sealed at their ends by flat faces of adjacent blocks.

2. A masonry construction made of hollow building blocks and mortar, each block having voids extending from end to end and having internal webs, said construction comprising courses of 5 said blocks some with the voids horizontal parallel to the wall and some with the voids vertical, other courses of said blocks, wherein the blocks have their voids vertical where they were horizontal in the adjacent course and horizontal where they 10 10 were vertical, whereby the voids are sealed at their ends by flat faces of adjacent blocks, and blocks of rectangular cross-section having through voids, set vertically to make closures at the corners, there being an additional wide and thin block set 15 endwise adjacent the narrow side of each corner block and extending beyond the same to bond with the block adjacent the wide side of the corner block.

3. A hollow building block which, when laid 20 with its voids horizontal, comprises vertical and horizontal shell members, two internal vertical webs adjacent the vertical shell members and two closely adjacent internal horizontal webs continuously spaced from each other from vertical web 25 to vertical web, extending transversely therebetween and disposed equidistant from respective horizontal shell members.

4. A hollow building block of rectangular cross-section, having parallel voids extending from end 30 to end, said block when laid with the voids horizontal having a shell composed of two vertical members and two horizontal members, two internal vertical webs spaced adjacent the vertical members and periodically connected therewith, 35 and two cross webs equidistant from respective horizontal members, connecting the internal ver-

tical webs and continuously spaced from each other from vertical web to vertical web.

5. A masonry construction made of hollow building tile, bricks and mortar, comprising surmounting courses of brick and mortar with occasional header courses backed up by surmounting courses of hollow tile, such tile providing spaces of sizes adequate to receive the projecting headers with upper and lower mortar beds, said headers extending materially more than half way and less than three quarters of the way across the hollow tile thereby producing a wall having a width greater than that of two bricks side by side, laid flatwise, and less than that of three bricks side by side and laid flatwise. 10 15

6. In masonry construction, a wall composed of hollow building blocks with through parallel voids, bricks and mortar, said wall comprising surmounting normal courses of brick and mortar with occasional header courses, said blocks when 20 set with their voids horizontal being of heights corresponding to the height of a plurality of bricks plus a number of mortar joints one less than the number of bricks, the wall having blocks set as aforesaid opposite and horizontally aligned 25 with such plurality of bricks of the normal brick courses, other blocks of the same section as those just mentioned being set with their voids vertical and overlapped by the inwardly extending header brick, said other blocks set as stated, corresponding in height to the combined height of the adjacent normal brick courses plus their separating mortar joints, and separate header blocks located 30 between the block courses aforesaid and in horizontal alignment with the header brick. 35

FREDERICK HEATH.
